Des. 226,262
Patented Feb. 6, 1973

226,262

MOBILE DRILL UNIT

Arthur J. Trueblood, Salt Lake City, Utah, assignor to
Western Road Machinery Company, Salt Lake City,
Utah

Filed Jan. 4, 1971, Ser. No. 103,945

Term of patent 14 years

Int. Cl. D12—09

U.S. Cl. D14—3 A

FIG. 1

FIG. 2

FIG. 3

FIG. 5

FIG. 6

FIG. 1 is a perspective view of the mobile drill unit showing my new design;

FIG. 2 is a top plan view thereof;

FIG. 3 is a side elevational view thereof;

FIG. 4 is a side elevational view thereof;

FIG. 5 is a front view thereof; and

FIG. 6 is a rear view thereof.

The elements shown in broken lines are included for illustrative purposes only.

I claim:

The ornamental design for a mobile drill unit, as shown and described.
